MOLD FOR CONCRETE.

1,214,829.

Specification of Letters Patent.

Patented Feb. 6, 1917.

Application filed September 11, 1913. Serial No. 789,332.

To all whom it may concern:

Be it known that I, JOSEPH F. ROSS, a citizen of the United States, residing at Ipswich, in the county of Essex and State of Massachusetts, have invented new and useful Improvements in Molds for Concrete, of which the following is a specification.

This invention relates to improvements in concrete molds.

10 More particularly it relates to mold ties of the style that pass within the mold, and remain embedded in the concrete when the mold is removed. The purpose is to provide a tie by which a face of concrete with a 65 good finish may be made at small cost; and it is particularly useful in connection with molds of the less expensive sort, such as are commonly used for general construction work, although the invention is applicable 70 to other ways with advantage.

The invention is here described as it may be applied in a common type of work, where wooden uprights or supports are lined with boards to form the mold for a wall of a 25 building. In such cases it is customary to hold the walls of the mold together by wires looped around opposite uprights and passing through the mold. When the mold is taken down the ends of these wires are 30 clipped at the face of the concrete. If the wires be left thus, discolorations of the surface result from iron rust, so that various expedients are employed to avoid leaving any of the tie exposed, such as by chipping 35 out the concrete, cutting the wire behind the surface and then filling with other concrete the hole that has thus been made. Such a method obviously involves considerable expense and furthermore does not make a very 40 neat finish, on account of the patching.

It is an object of the present invention to save this labor without materially increasing the cost of the tie that is left embedded, or of the mechanism employed, and to leave 45 a surface of concrete which is practically perfect when the mold is taken down, involving little or no labor cost for putting it in final condition.

Appliances embodying the invention by 50 which these objects are accomplished may be made and used in several different forms, and may be varied according to the needs of the particular work in hand; but the following description will disclose the principles 55 on which these appliances may be designed

and modified to such particular needs, and show the forms which I at present consider most complete and useful.

It is an object of the patent to cover in the claims such features of novelty as exist 60 in the matter disclosed.

In the accompanying drawing the figure is a perspective, showing in elevation a section through a mold in which various forms of the invention are embodied.

Referring to the drawing 10 indicates 65 uprights or supports which are represented as wooden timbers of the ordinary 2x4 size, but which may be of any other size or shape or material. Boards 11 line the insides of 70 these supports, forming the face of the mold; and the whole is drawn and held together by a composite tie consisting of the wire 12, a link 13, and a screw threaded rod or bolt 14. As represented in the upper 75 part of the drawing a washer 15 and a nut 16 on the bolt also form part of the tie. The invention is thus represented as it may be combined with the old style of tie, in that the wire 12 is fastened at the right by being 80 looped around the upright 10. When this mold is taken down the loop will be cut at the surface of the concrete. This would be open to the objection stated in the preamble, if that surface of the concrete were to 85 be exposed; but in some buildings the inside of the walls is so covered that this style of tie may be used and in the case of a retaining wall for earth this face of the wall is subsequently buried where it is not visible. 90

However, the style of fastening the other end of the link 13 to the mold wall, seen at the left, might be used for the fastening to the mold wall at the right if it were desired 95 to treat that as a face of the finished concrete. In the construction illustrated, the link 13, which is a square, or otherwise non-circular block, has at one end a hole 20 through which the wire 12 may pass, and at its other end, being the end toward the 100 boards 11 that form the face of the concrete, a hole 21 adapted to receive the screw threaded end of the bolt or rod 14. In the form illustrated in the upper part of the drawing this latter has screw threads in two 105 places, running in opposite directions, the thread adapted to engage in the hole 21 within the mold being a right hand thread and the other, on the part of the bolt that extends outside the mold, being a left hand 110

thread and carrying the nut 16 in such position that the nut is adapted to be screwed up against the outside of the upright 10. Between these threads is a space in which 5 the bolt is left at full size with smooth round surface, uncut by either thread. The relative dimensions of various parts are such that the link block 13 may be positioned one, two or more inches within the mold 10 from the face of the wall 11 with the unthreaded portion of the bolt 14 entering the hole 21 which is countersunk a little to receive it, and also passing into the mold wall 11. In other words, when the device is in 15 use, one thread is incased in the link block 13, and the other thread is wholly within or on the outer side of the wall of the mold, so that that portion of the bolt which is exposed to contact with concrete is straight and 20 smooth. Any suitable means is provided to turn the bolt 13, represented in Fig. 1 by a flattened head 17 formed on that end of the bolt after the nut 16 has been put in place.

In use, the mold is formed by erecting the 25 supports 10 and placing the boards 11 thereon in the ordinary way. Holes are bored to admit the wire 12 and the bolt 14, the hole for the latter being in this case represented as going through the support 10 and one 30 of the boards 11, while the hole or holes for the wire are merely through the boards, the wire being looped around the right hand support 10. The wire having been thus looped between the support 10 and the link 35 block 13 the workman inserts the bolt 14 through the other wall and screws it into the block 13 to the desired distance. The nut 16 is then whirled on its thread until it engages the outside of the support 10, after 40 which the turning of the bolt is resumed in its former direction thus shortening the composite tie until the mold faces are at the desired distance apart. The mold is then ready for use. The walls are drawn 45 together during the last mentioned operation, because right handed rotation of the bolt, relative to the nut 16, propels the nut 16 away from the bolt head 17, carrying with it the adjacent support 10, thus drawing 50 the two walls together. The same rotation also tends to screw the bolt farther into the block 13. If that block be held against rotation at this time the drawing effect on the two walls will be increased 55 because of the diversity of threads; while if the bolt has already reached its utmost depth in the block 13 that block will rotate in company with the bolt, and will thus twist the wires 12 somewhat, thus making 60 them taut, and incidentally helping draw the walls together.

When the mold is filled with concrete none of it can enter the hole 21 because the full body of the bolt 14 fills the entrance 65 to that hole; and none can enter the hole

where the bolt 14 passes through the face of the mold, because that hole has been bored the same size as the bolt. As the bolt is smooth and cylindrical, and of maximum diameter at the only places where the concrete comes against it, it may be easily removed by being turned over to the left after the concrete has set. This screws it out of the block 13 leaving that embedded in the concrete. No difficulty is experienced in 70 this, because the non-circular shape of the block prevents its turning. The bolt passes easily out of and through the concrete mass because its threads are not at all engaged with the concrete, and are no larger than 75 the hole made in the concrete by the full size portion of the bolt. When the mold is taken down, no metal is exposed at the face of the wall, and no pit or defacement is visible. Only the small hole left by the bolt 80 is seen, which may be three-eighths of an inch or less in diameter, and which can, if desired be quickly and cheaply plugged 85 with fresh concrete.

The invention is also adapted for use with 90 an iron band 12' instead of the wire 12; and the link block 13' is then shaped accordingly, with a larger hole 20' and also with a notch 22 to seat a wire, if desired, in place 95 of the metal band 12'. The bolt 14' is also different from the structure 14 above described in that its head 18 is integral with the body or rod portion of the bolt, and in that there is no nut 16 next the head, nor thread there, but only the thread at the 100 point of the bolt. The hole 21' for receiving the point of the bolt is drilled completely through into the opening 20' of the block 13'; and the thread on the bolt is long enough so that it can screw into the 105 block to whatever distance is necessary to draw the mold wall to its desired position. Perhaps it would be more accurate to say that in this form the functions of the nut 16 and the head 17 are combined in the 110 integral head 18, because this head 18 is the means by which the bolt 14 is rotated and is also the means for engaging the outside of the support 10. The simplicity of this structure is obvious. By designing the 115 parts suitably, according to the dimensions of the work on which they are to be used, the thread of the bolt may be short enough so that it is fully embedded in the block 13; but if not, it is desirable in using this appliance to dip this part of the bolt in slush 120 or grease before installing it, to facilitate its removal after the concrete has set.

The invention may also be applied to a 125 combined tie and strut. In this case a duplicate bolt 14 takes the place of the wire 12 or hoop 12', and the link block 23 has in each end a hole 21 with internal screw threads for receiving one of the bolts 14. The form illustrated is that of a drawn 130

metal tube, with a pipe thread cut internally at each end, the tube being crushed in the middle to make it non-circular; but a solid member might be substituted. And in this 5 case a further modification of the arrangement of threads on the bolts 14 is shown, in that the thread is a continuous one from the point up to the head of the bolt; although either of the other styles illustrated might 10 be used. This single thread carries the external nut 16 above described, and also a nut 19 comprising an abutment adapted to engage an inner face of the mold wall. As illustrated, this inner face is obtained by 15 cutting a transverse channel or recess in the inner face of the support, providing a surface at 10" against which the nut 19 may bear, so that the presence of the nut does not interfere with the facing of boards 11. Radial holes may be provided in the sides of 20 this nut to facilitate the turning of the nut, after the manner of a capstan, in order to adjust its position on the bolt 14, or the edge of the nut may be knurled or other means 25 provided for turning it. The manner of using this form of the invention is to insert the opposite bolts 14 in the link block 23 to the desired distance; then to set the spacing or abutment nuts 19 at the proper positions 30 thereon for the correct spacing of the interior faces of the mold; and then by turning the nuts 16 to push the supports up tightly against these spacing nuts or abutments 19. In taking down this mold the bolt 14 can be 35 easily unscrewed after one or both nuts have been loosened, and comes out leaving the link block 23 embedded in the concrete, with only a small hole at the surface, as before. The part thus embedded, both in this case 40 and in the previous cases, is available at any future time for reception of a screw stud, by the aid of which the mass of concrete may be lifted and handled, if it be a movable piece such as a building block; and 45 the presence of this embedded member with enlarged ends also serves as a reinforcement for the concrete. The hole in the face of the concrete is relatively small, because the bolt engages the embedded block internally. No way has hitherto been known, 50 so far as I am aware, to make a tie which is also a strut without having a relatively large original exposure of metal or other foreign material on the face of the concrete. 55 The method of interior engagement herein disclosed permits of the abutment 19 being placed outside the face of concrete, with only a narrow neck of metal passing through that face; and thus the relatively large diameter which a good abutment must necessarily occupy does not become a cavity in the face of the concrete.

Many variations other than the above may 60 be made in the application of the invention, within the scope of the appended claims. In

particular, however, I think it well to mention that the method of engaging the rod internally in the link block is not necessarily that of screw and thread, although that is the form which I at present believe to be best; and that the means of engagement between the link block and the wire or hoop need not be an eye-hole as illustrated, but may be a hook or some other suitable means, if such be preferred.

The use of wire for the portion 12 of the tie affords an economy of material and of labor cost, as compared with systems by which a machined and heavier part is left embedded. The carrying of this rod 14 from the link block directly and integrally to the outside of the support 10 affords an economy of labor in that when the bolt which holds the support is removed the whole separation and removal of the separable portion of the tie has been incidentally accomplished, without necessity for a second operation. The relative smallness of the diameter of the bolt 14 makes it unscrew readily through the concrete if it happens that its threads are not fully housed therefrom when the mold is filled.

I claim:

1. A mold comprising walls and a composite tie therefor passing through the mold, one component of the tie being within the mold at a distance from the mold face and having no part reaching the mold; another engaging the first removably, adapted to rotate it, extending out through the mold wall, and provided with means by which it may be rotated; and a third component rotatable by the first, connecting the first with the other mold wall, and adapted when rotated, to shorten the tie.

2. A mold comprising walls and a composite tie therefor passing through the mold, one component of the tie being within the mold at a distance from its face; a second component engaged removably therewith, extending out through the mold face, and adapted to rotate the first mentioned component; and a third component engaged between the first and the other mold face and adapted to be shortened by being twisted when the first mentioned component is rotated.

3. A mold comprising walls and a composite tie therefor passing through the mold, one component of the tie being a link ending within the mold at a distance from the mold face, with space of the mold between it and said face whereby it will become enveloped by material filling the mold; and another component being a rod screw-threaded into said end of said link, passing outside the mold wall, and there having screw threads in the reverse direction and a nut thereon adapted to engage the outside of the mold wall.

4. A mold comprising walls and a composite tie therefor passing through the mold, one component of the tie being a link set within the mold and having two holes 5 through it perpendicular to each other; one of said holes extending toward the adjacent mold face and having means internally to engage a second component; and the other of said holes extending substantially parallel 10 to the mold face and adapted to engage a third component, said second component, projecting outside the wall; means thereon engaging the exterior of the wall; and said third component, looped through said hole 15 and adapted to extend integrally to and be connected to the opposite face.
5. A composite tie for a mold comprising a wire loop adapted to be engaged with one wall of the mold, a link within the mold 20 space having a hole through which the wire is looped and a bolt adapted to engage the

link removably and provided with means to engage the other mold wall.

6. A mold comprising walls and a composite tie therefor passing through the mold; 25 one component of the tie being within the mold at a distance from the mold face; another engaging the first removably, adapted to rotate it, extending out through the mold wall, and provided with means by which it may be rotated; and a third component 30 engaged by the first, integrally separate therefrom and rotatable thereby, connecting it with the other mold wall and adapted, when rotated, to shorten the tie. 35

Signed by me at Boston, Mass., this third day of January, 1913.
